Fig. 4

FIG. 1 is a top plan view of the powdered coffee dispenser of my design.

FIG. 2 is a front elevational view.

FIG. 3 is a side elevational view, and

FIG. 4 is a sectional view taken through the line 4—4 of FIG. 2.

The undisclosed side of the dispenser is substantially the same in appearance as the side shown.

The dominant features of the design reside in the full line portions.

I claim:

The ornamental design for a powdered coffee dispenser, substantially as shown and described.
